CLAIM

The ornamental design for a rear combination lamp, as shown and described.

DESCRIPTION

FIG. 1 is a perspective view of the new design for a rear combination lamp showing a first (left) embodiment;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

A second (right) embodiment is a mirror image of the embodiment shown in FIGS. 1-7 and is not shown.
